UNITED STATES PATENT OFFICE.

GRANT D. BRADSHAW, OF PITTSBURGH, PENNSYLVANIA, ASSIGNEE TO BLAW-KNOX COMPANY, OF BLAWNOX, PENNSYLVANIA, A CORPORATION OF NEW JERSEY.

FLUID SEPARATOR.

Application filed June 20, 1923. Serial No. 646,535.

This invention relates to improvements in fluid separators, and particularly to the type of separator disclosed by the Patent No. 1,336,870, issued to H. H. Tracy, April 13, 5 1920. For details of the separator not material to this invention reference may be had to the said patent. The object of the invention disclosed by said patent is to separate foreign substances and particularly moisture 10 from gases, and a particular object is to separate moisture from steam which is being used from steam power boilers. One object of this present invention is to provide means for controlling the moisture which is separated 15 from the steam so that a portion only is removed from the boiler and the remainder is retained in the boiler. Other objects of the invention will be apparent from a consideration of the following description.

20 Of the accompanying drawings, Fig. 1 is a transverse sectional elevation of a fluid separator, which embodies the features of my invention, taken along the line 1—1 of Fig. 5; Fig. 2 is a fragmental sectional plan view 25 along the line 2—2 of Fig. 1; Fig. 3 is a fragmental plan view of an upper corner of the separator; Fig. 4 is an enlarged fragmental bottom view of one corner of the separator; and Fig. 5 is a reduced elevation of the separator mounted in a boiler.

30 It is common, in order to separate impurities such as moisture from the steam which is being used, to pass the steam through a separator while it is on its way from the interior of the boiler to the steam mains of the system. The separator ordinarily comprises some arrangement of baffles around which the steam must pass and which are so arranged that, while the steam will pass through by a more or less circuitous route, the impurities such as moisture will be retained by the baffles and will pass out of the boiler or back into the boiler as may be desired.

The apparatus which I prefer herein to 35 illustrate my invention comprises a casing having end pieces 2, a top 3 and a bottom 5 inside of which are mounted systems of baffles 6. The casing when in use is mounted within the boiler and the steam passes around and between the baffles 6 into the interior chamber 7 and passageway 11 of the separator; and, then, ordinarily, the steam passes through the outlet 10 out of the boiler into the steam main of the system. As the steam 40 passes between the baffles the moisture there-

in is stopped in its flow by the baffles and it runs downwardly and into the passage 8 and through the pipe 9 to any point outside of the boiler to which it is desired to discharge the water. The passageway 11 is ordinarily 60 provided with side plates 12, a bottom plate 13, and an upper plate 14, the plate 14 being elevated above the side plates so as to leave passageways 15 through which the steam may enter to the interior passageway and then may pass out through the steam outlet 10 which connects with the passageway 11 by means of the T, 4.

In the use of a steam boiler, as is well understood, more or less impurities, such as 70 calcium sulphate and other minerals, are continually entering the boiler with the feed-water, and as the water in the boiler evaporates these minerals are precipitated and must be removed by blowing out more or less 75 of the water from the boiler, or in some other manner. When a steam separator is used, the water which is separated from the steam contains more or less minerals and other impurities and if this water is allowed to pass 80 out of the boiler it will carry with it these impurities. On the other hand, if this water is returned to the boiler the impurities are not removed. As a consequence, a boiler equipped with an efficient separator which returns 85 the separated water to the boiler will accumulate more impurities in a given time than when a separator is not used, as then more or less moisture and its impurities pass 90 out with the steam.

In order to prevent any of the water which 95 enters the baffles 6 from returning to the boiler I provide a baffle, such as the plate 16, positioned on each side of the separator outside of the main bank of baffles 6 and extending the full length of the baffles. With this baffle it is impossible for the water which passes beyond the plate 16 to flow back into the boiler and instead it flows onwardly into the passageway 8 and finally into the outlet 100 pipe 9. The ends 2 of the casing fit snugly against the respective ends of the plate 16, and, hence, prevent the water from flowing around the ends of the plate and back into the boiler. These baffles 16 also diminish the 105 tendency of the incoming steam to mix with the separated water and carry it along with the steam, as the incoming steam must pass over the upper edges of the baffles 16, and the separated water is below these edges.

However, I have found it desirable in many cases, especially where the surging of the water in the boiler is very great, to provide further means for separating the water from the steam.

The means which I prefer for such a purpose comprise auxiliary separators 17 positioned on each side of the main separator and outside of the plates 16. I prefer for this purpose two rows of baffles 18 similar in general to the baffles 6 except that the lower ends of the baffles 18 are open. The steam passing through these auxiliary separators leaves behind it the greater portion of the moisture, and this moisture merely runs down the baffles 18 and back into the boiler without passing beyond the plate 16. In this manner a large proportion of the water is separated before the steam enters the main separator. As a consequence, the amount of water still remaining in the steam is so small that there is no danger of flooding, the separator and the water is ultimately separated entirely from the steam so that the highest efficiency is obtained. With these auxiliary separators, the plate 16 acts as a baffle to prevent the separated water from passing into the main separator. Although the lower ends of the baffles 18 are open, yet, without the plate 16, there would be a tendency of the steam to carry a material portion of the partly separated water onwardly into the main separator.

Any suitable means may be used for connecting the auxiliary separators to the main separator. I prefer plates 19 entirely closing the upper ends of the baffles 18 and the chamber 20 between the two sets of baffles, and the supporting strips 21 and 25 which hold the rows of baffles 18 in place without materially closing the lower ends thereof. The baffles 18 are held at their lower ends by strips 28 and 29 which are fixed to the respective strips 21 and 25. I have found, however, that it is very difficult to anticipate the best arrangement of the various parts of the separator in order to meet working conditions of particular boilers, and also that it is frequently desired to vary the arrangement of the parts in accordance with variations in conditions of the boiler. I, therefore, provide means for adjusting the distance between the auxiliary and the main separators, and also the distance between the two rows of baffles 18. Varying these distances varies the amount of water that will be separated and affects materially the relative amounts that will flow back into the boiler and on into the main separator. For instance, as the rows of baffles are separated further the angular changes in velocity of the steam decreases and hence the amount of water separated from the steam also decreases. To adjust these distances I provide slots 22 in the plates 19 and, corresponding slots in the strips 21, so as to vary the distance between the two

separators, and I provide slots 23 in the plates 24 and corresponding slots in the strips 25, so as to vary the distance between the two baffles 18. The inner baffles 18 are fixed to the plates 19 and strips 21 and the outer baffles 18 are fixed to the plates 24 and strips 25. Bolts 26 connect the plates 19 and the top plate 3 and also the strips 21 and the bottom plate 5. The bolts 27 connect the plates 24 and 19 and also the strips 25 and 21.

It will, therefore, be seen that, in conjunction with the ordinary means for separating the water and the other impurities from the steam, I have provided means for effectively controlling the relative amounts of water that flow back into the boiler or onwardly into the separator, and these means are such that all of the separated water may be passed into the separator by leaving off the auxiliary separators 17 and using the plates 16, or, by the use of the auxiliary separators, a large portion of the water may be passed back into the boiler, whatever relative proportion may be desired; and at the same time the moisture and impurities by means of these auxiliary separators may be separated entirely from the steam, and all flooding of the separator is avoided.

I claim as my invention:

1. The combination of a main steam separator and an auxiliary separator connected in series with said main separator, each of said separators being vertical and of substantially the same height and length, and each comprising a plurality of steam baffles, said auxiliary separator being adjustably positioned outside of and a material distance away from said main separator casing.

2. The combination of a main steam separator and an auxiliary separator connected in series, each of said separators being vertical and comprising a plurality of steam baffles, said auxiliary separator being positioned outside of and a material distance away from said main separator, the lower ends of the baffles of said main separator being closed, and the lower ends of the baffles of said auxiliary separator being open.

3. The combination of a main steam separator having a closed casing and an auxiliary separator, each of said separators comprising a plurality of steam baffles, said auxiliary separator being positioned outside of said main separator casing, and a water baffle positioned between said separators and adapted to prevent water from flowing outwardly from the inner separator.

4. The combination of a main steam separator, and an auxiliary separator, each of said separators comprising a plurality of steam baffles, said auxiliary separator being positioned outside of and a material distance away from said main separator, and means for adjusting the distance between said separators, comprising overlapping flanges, one

of said flanges having openings therethrough and the other of said flanges having slots therethrough normally registering with said openings, and means passing through said 5 registering slots and opening for clamping said respective flanges together.

5. The combination of a main steam separator and an auxiliary separator, each of said separators comprising a plurality of steam 10 baffles, said auxiliary separator being positioned outside of and a material distance away from said main separator, and means for adjusting the distance between the baffles of one of said separators.

15 6. The combination of a main steam separator and an auxiliary separator, each of said separators comprising a plurality of steam baffles, said auxiliary separator being positioned outside of and a material distance 20 away from said main separator, and means for detachably uniting the separators, said means comprising overlapping flanges fixed respectively to the separators, each of the flanges of one of said separators having 25 an opening therethrough and each of the flanges of the other separator having an open slot therethrough registering respectively with said openings, and detachable means passing through said slots and openings for holding said flanges together.

30 7. The combination of a main steam separator, and an auxiliary separator, each of said separators comprising a plurality of steam baffles, said auxiliary separator being positioned outside of and a material distance away from said main separator, and means for adjusting the distance between the baffles of one of said separators, said means comprising overlapping flanges fixed to the 35 respective baffles of the separators, one of said flanges having openings therethrough and

the other having open slots registering with said openings, and detachable means passing through said slots and openings for holding said flanges together.

45

8. The combination of a main steam separator and an auxiliary separator connected in series, each of said separators comprising a plurality of vertical steam baffles, said auxiliary separator being positioned outside of 50 said main separator, and means for adjusting the distance between said separators.

55

9. The combination of a main steam separator having a closed casing and an auxiliary separator, each of said separators comprising 60 a plurality of steam baffles, said auxiliary separator being positioned outside of said main separator casing, and a water baffle positioned between said separators and adapted to prevent water from flowing outwardly from the inner separator, said baffle being fixed to the bottom of the main separator and extending upwardly less than half way to the top of the main separator baffles.

65

10. A fluid separator comprising a casing with one side open and having a steam outlet, a series of steam baffles positioned in said open side, means forming an inner passageway between said baffles and outlet, said passageway communicating with said outlet and said means having a steam inlet along its upper side facing said baffles and in open communication with, said separator having a liquid passageway in said casing at the lower portion thereof, and a plate fixed to the bottom of the opening of the said casing and extending along the open side thereof, and projecting upwardly less than one-half the height of said opening.

70

In testimony whereof, I hereunto set my 75 hand.

GRANT D. BRADSHAW.
